United States Patent Office.

JOSEPH W. GARDNER, OF SHELBURNE FALLS, MASSACHUSETTS.

Letters Patent No. 103,867, dated June 7, 1870.

IMPROVEMENT IN ATTACHING HANDLES TO CUTLERY.

The Schedule referred to in these Letters Patent and making part of the same

To all whom it may concern:

Be it known that I, JOSEPH W. GARDNER, of Shelburne Falls, in the county of Franklin and State of Massachusetts, have invented certain new and useful Improvements in Fastening Table-Knives and other Cutlery to their Handles; and I do hereby declare the following to be a full, clear, and exact description of the same, reference being had to the accompanying drawings making a part of this specification, in which—

Figure 1 represents a view of a completed knife;
Figure 2 represents a section through the same; and

Figure 3 represents one of the cheek-pieces detached from the knife, and turned over to show its interior.

Similar letters, where they occur in the separate figures, refer to like parts in all of the drawings.

This invention relates to a very simple, cheap, and efficient way of uniting a short-tanged knife or fork to its handle in a firm and unyielding manner.

To enable others skilled in the art to make and use my invention, I will proceed to describe the same, with reference to the drawings.

The blade A of the knife, or shank of a fork, is made with a short dovetailed tang, a, and with a small tapering piece, c, projecting rearward from the tang.

The handle B, made of any of the known material used for the purpose, has a recess formed in it to receive this tapered portion c.

Two side or cheek-pieces, C C, are then prepared, as more distinctly seen in fig. 3, with a shoulder, as at e, so as to lie up close to or into a recess in the handle, and with a dovetail recess at f, to receive the dovetailed tang a.

Each side or cheek-piece receives into its recess about half the thickness of the tang, and, after clasping it, they meet, as seen in fig. 1, and are riveted through each other and through the tang at g, and through each other and through the handle at h, making a strong union of the parts, and a very neat finish to the knife or other article.

Having thus fully described my invention,

What I claim, as a device for fastening knives and other articles to their handles, is—

In combination with the dovetailed tang a, the similarly-recessed side or cheek-pieces C C for holding themselves and the blade or fork to the handle, by suitable rivets, as described and represented.

J. W. GARDNER.
